(57) CLAIM

I claim the ornamental design for a tool box, as shown and described.

DESCRIPTION

FIGS. 1-7 depict the tool box of the present invention. FIG. 1 is a perspective view of a tool box showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Any broken lines shown in the drawings are for the purpose of illustrating portions of the tool box that form no part of the claimed design.
